UNITED STATES PATENT OFFICE.

JOSEPH S. WILLIAMS, OF RIVERTON, NEW JERSEY.

RESILIENT-TIRE CONSTRUCTION AND WHEEL EQUIPMENT.

1,258,968.

Specification of Letters Patent.

Patented Mar. 12, 1918.

Application filed December 8, 1909, Serial No. 332,047. Renewed June 12, 1917. Serial No. 174,407.

To all whom it may concern:

Be it known that I, JOSEPH S. WILLIAMS, a citizen of the United States, residing at Riverton, county of Burlington, State of New Jersey, have invented a new and useful Resilient-Tire Construction and Wheel Equipment, of which the following is a specification.

My invention consists of a novel construction of a resilient tire and wheel equipment which will give in practice marked and advantageous results, provision being made for reinforcing the construction to any desired extent.

It further consists of novel features of construction, all as will be hereinafter fully set forth.

For the purpose of illustrating my invention, I have shown in the accompanying drawings those forms which are at present preferred by me, since the same have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a transverse section of a tire embodying my invention.

Fig. 2 represents a transverse section of another embodiment of my invention.

Fig. 3 represents a transverse section of another embodiment of my invention.

Figs. 4, 5 and 6 represent, respectively, transverse sections of other embodiments of my invention.

Figs. 7, 8 and 9 represent longitudinal sections of the embodiments seen in Figs. 1, 2 and 3, respectively.

Figs. 10, 11 and 12 represent longitudinal sections of the constructions seen in Figs. 1, 2 and 3, respectively.

Figs. 13 to 22 inclusive, represent transverse sections of other embodiments of my invention.

Similar numerals of reference indicate corresponding parts in the figures.

Referring to the drawings.

In all the embodiments of my invention herein shown, I have illustrated a construction in which a resilient reinforcement is circumferentially and transversely disposed

between the rim and the tread.

Referring first to Figs. 1, 2 and 3, an

annular resilient core construction is provided which is transversely elongated or of elliptical or flattened construction in cross section with annular metal reinforcements 60 34 in the seating parts and flexible metal 35 supporting the outer face of the solid cushioning cores 36 which are designed to be compressible and provide support without the use of fluid content or by means of fluid 65 content in the transversely disposed inflatable tube 37. Such fluid content may be of elastic or incompressible nature or of viscous material and the position of the tube under fluid content is indicated at 38 in 70 Figs 10, 11 and 12.

The transversely elongated arrangement of the resilient cores 36, tensile and flexible metal 35, inflatable tubes 37 and fluid content 38 are embodied as a unit of construction within an outer casing 39 which is circumferentially inextensible and is of elongated or flattened form in transverse section. Detachable and demountable tire equipments are provided having rings 40 80 and 41 which grip the seatings of the construction and hold the same under compression in firm wheel equipment under all conditions of inflation and deflation. The core 36 in Fig. 1 is formed of resilient rubber or a mixture of rubber and any other desired material reinforced transversely by fabric or fiber 42. The tensile and flexible metal 35 has a layer of tensile cushioning material 43 on the outer face thereof to 90 serve as a cushioning layer and a bond between the member 35 and the tread portion of the outer casing 39 and to obviate the strain thereon and on the fibrous reinforcement 44 as the member 35 responds to the 95 deflected action of load strain and inequalities of the road surface. 45 designates a fluid-tight fiber and rubber tube incasing the core 36 and is transversely disposed and of flattened elliptical formation in cross section. The seating parts of the outer casing 39 are reinforced by annular members 47 and 48 preferably of metal which extend into the channel seating between and formed by the clencher rings 40 and 41 which latter 100 are seated upon the rim tire 49. 50 designates an outwardly extending annular flange at one side of the rim 49, the opposite side being provided with an inwardly extending annular flange 51 with which interlocks the 105 transversely divided locking ring 52 which forms a supporting or retaining member for

the ring 41 which when forced transversely toward the ring 40 impresses the elastic parts of the seatings so that the tire will be firmly gripped and retained under compression in wheel equipment.

Any desired type of inlet passage may be provided with the conventional type of valve mechanism.

In the embodiment seen in Fig. 2, the core 10 has a flattened formation instead of the flattened arch formation seen in Fig. 1. The demountable ring 53 is formed of two annular transversely divided rings 54 and 55 each of which are provided with circumferential locking parts at 56 to form when united the demountable rim 53. 57 and 58 designate annular projections co-fitting and interlocking in the annular groove of the rim 49.

20 In the embodiment seen in Fig. 3, the terminals 59 and 60 are in engagement with the seating members 34' and 61 and the clencher rings 62 and 63 which latter are clamped to the rim 64 by bolts 65.

25 In the embodiment seen in Fig. 4, the core construction 36' is enveloped by a fluid-tight tube 66 conforming to the outer contour of the core 36' and the inner periphery of the outer casing 39'. The terminals 39' and 30 60' extend over the reinforcing member 34' so that the core is provided with a seating throughout its width. The terminals of the outer casing 39' are provided with annular reinforcements 47' and 48'. Such terminals 35 are located in the annular channel formed by the clencher member 70. The outer face of the casing 39' is provided with annular grooves 72 with which interlock annular projections 73 of a detachable tread 67 40 against which the outer casing 39' is held in compressive engagement. In some cases it is advantageous to employ an annular and transversely disposed resilient reinforcing member 74. The detachable tread is 45 provided with annular reinforcements 75 and with an annular tensile and flexible reinforcing member 76 covering the width of the cushioning core 36'. The inner channel space of the member 69 is seated on the rim 49 and locked in position by the projections 68' and 70 on the inside face of the member 69. 71 designates bolts passing radially through the rim 64, the rim 49, the annular member 69 and into the annular member 34' 55 so that the terminals 39' and 60' are compressed thereby and all the parts united in wheel equipment.

In the embodiment seen in Fig. 5, 70' is the cushion core seated upon the 60' demountable rim member 69' which is channeled on its inner face to interlock with the rim 49. The core 70' is located in the outer channel part of the member 69' and the covering of the core has an annular band of 65 tensile and flexible metal 71 which renders

such portion circumferentially inextensible. This member 71 is located within the outwardly projecting sides of the seating member 69' so that the tire construction is firmly secured in position and reinforced against 70 torsional strain and uniformly supported throughout the width of the core. The outer face of the core covering 39' is equipped with a detachable tread 67 interlocking in the same manner as the detachable tread seen in Fig. 4.

In the embodiment seen in Fig. 6, the demountable member 69' corresponds in construction and is secured in position in the same manner as that seen in Fig. 5. In addition to the annular reinforcing member 34', annular reinforcements 47 and 48' may be employed.

My invention may be employed either with or without fluid content and in Figs. 7, 8 and 9, I have shown the fluid content as being omitted while in Figs. 10, 11 and 12, the fluid content is employed.

In the embodiment seen in Fig. 13, the transversely arranged core 36 has an annular metal member 35' of steel or other metal of elliptical form in cross section filled with rubber or a mixture of rubber transversely reinforced by fibrous or other material 77 surrounded by fabric or rubber structure 95 66' which latter is mounted upon an annular seating member 79' having inwardly projecting flanges extending into the seating part which is adapted to be received and rest upon the rim and be secured thereto in any 100 desired manner. The core and the other parts just described are enveloped by the outer covering 39' which is provided with a flattened tread.

In the embodiment seen in Fig. 11, the 105 outer casing has a flattened tread and is under radial compression in the transversely divided channel member 69', a metal reinforcement 78 being provided and the seating member 69' having an annular projec- 110 tion 83.

In the embodiment seen in Fig. 15, the resilient core 36' has an annular flexible metal member 79 approximating the width of the core and a portion of the core covers the 115 outer face of such member which is provided with a cushioning layer 43 on its outer face. This core is enveloped by fabric layers 66' corresponding to the outer form of the core 36' which latter is backed by the 120 reinforcing member 80 having inwardly projecting flanges 81 with which co-fit the transversely divided demountable rim 69'.

In the embodiment seen in Fig. 16, reinforcements 79' are shown having inwardly 12 extending flanges extending into the seating parts of the transversely divided annulus 69'.

The outer casing 39' may be detachable from the core 36' and operate as an in- 13

wardly opening construction and be combined with an annular transversely divided member 84 as seen in Fig. 17, in which metal reinforcements 86 and 87 overlap and 5 interlock with the member 84.

In the embodiment seen in Fig. 18, outer and inner annular members 88 and 89 are provided with resilient cushioning material 36" or mattress 36'" between the members 10 88 and 89 or the channels formed therein.

The outer casing 39' cofits and is seated upon a demountable member 84'. A detachable tread with inwardly extending side flanges is interlocked with the casing 39'.

15 In the embodiment seen in Fig. 19, the tire body is mounted on or formed with an annular metal member 92' exterior of which is the tire body 91 which is adapted to interlock with a detachable tread, while in the 20 embodiment seen in Fig. 20 the detachable tread has been omitted.

In the embodiment seen in Fig. 21, the construction corresponds substantially to that seen in Fig. 16 except that a rim equipment corresponding to that seen in Figs. 19 25 and 20 is employed instead of the rim equipment seen in Fig. 16.

In the embodiment seen in Fig. 22, the tire body 91 is mounted on a transversely 30 arranged core 36"" seated in the channel of the annular member 93 which latter is seated upon a flattened annular cushion 36⁵ mounted on the transversely divided demountable member 94 which interlocks with 35 the rim equipment. The tire body 91 is provided with an annular reinforcement 92' which is within the ends of the outwardly extending flanges of the member 93.

In accordance with my present invention, 40 an annular and transversely elongated body is provided which forms a non-collapsible and universal resilient truss. The flexible tension elements of the truss are annularly and transversely disposed and are arranged 45 substantially concentric relatively to the major transverse axis of the construction and preferably on both sides of such axis, with curvatures at the sides forming flexing tension abutments for the annular trans- 50 verse truss or trusses of the tension elements. I also employ an annular and transversely elongated cushion in abutting relationship with the annular and transverse tension truss or trusses. The curvatures at 55 the sides of the tension belt formed by the tension truss or tension element are yielding supported by the flexible cushioning material which substantially fills the space between said curvatures, and the cushion is 60 in abutting relationship with the annular and transverse tension truss throughout the length and width of the construction.

The tension of the truss, which is in the form of a tension belt, may be increased by 65 introducing fluid under pressure into the

cells of the cushion or into the fluid tight tube provided in the body for such purpose.

I also employ an annular and transversely disposed metal spring arranged substantially 70 concentric with the major transverse axis inwardly of the annular and transverse truss, or in other words of the tension belt.

It will now be apparent that I have devised a novel and useful construction of a 75 resilient tire construction and wheel equipment which embodies the features of advantage enumerated as desirable in the statement of the invention and the above description, and while I have, in the present instance shown and described preferred embodiments thereof which have been found in practice to give satisfactory and reliable results, it is to be understood that the same is susceptible of modification in various particulars without departing from the spirit or scope of the invention or sacrificing any of its advantages.

Having thus described my invention what I claim as new and desire to secure by Letters Patent is:

1. A wheel equipment, comprising an annular and transversely elongated body forming a non-collapsible and universally resilient truss, said body having flexible 95 tension elements annularly and transversely disposed and substantially concentrically arranged relatively to the major transverse axis, with curvatures at the sides forming flexing tension abutments for the annular 100 and transverse truss of the tension elements, an annular and transversely disposed metal spring arranged substantially concentric with the major transverse axis inwardly of the annular and transverse truss, and an annular and transversely elongated cushion in 105 abutting relationship with the annular and transverse tension truss.

2. A wheel equipment, comprising an annular and transversely elongated body forming a non-collapsible and universally resilient truss, said body having flexible tension elements annularly and transversely disposed and substantially concentrically arranged on both sides of the major transverse 110 axis, with curvatures at the sides forming flexing tension abutments for the annular and transverse trusses of the tension elements, an annular and transversely disposed metal spring arranged substantially 115 concentric with the major transverse axis inwardly of the annular and transverse truss, and an annular and transversely elongated cushion in abutting relationship with the annular and transverse tension trusses. 120

3. A wheel equipment comprising an annular and transversely elongated body forming a non-collapsible and universally resilient truss, said body having flexible tension elements annularly and transversely dis- 125

posed and arranged substantially concentric relatively to the major transverse axis, with curvatures at the sides forming flexing tension abutments for the annular and transverse truss of the tension elements, an annular and transversely disposed metal spring arranged substantially concentric with the major transverse axis inwardly of the annular and transverse truss, and an annular 5 and transversely elongated cushion having flexible cushioning material of yielding nature substantially filling the space between the curvatures at each side, and in abutting relationship with the annular and 10 transverse tension truss throughout the major width of the construction.

4. A wheel equipment, comprising an annular and transversely elongated body having a circumferentially inextensible tension belt arranged substantially concentric with the major transverse axis of the body in the outer portion of the body, an inner support for said belt, an annular and transversely disposed metal spring arranged substantially 20 concentric with the major transverse axis inwardly of said tension belt, and an annular and transversely elongated cushion between said belt and inner support.

5. A wheel equipment, comprising an annular and transversely elongated body having a circumferentially inextensible tension belt arranged substantially concentric with the major transverse axis of the body in the outer portion of the body, an inner support 30 for said belt, an annular and transversely disposed metal spring arranged substantially concentric with the major transverse axis inwardly of said tension belt, an annular and transversely elongated cushion between said belt and inner support, and fluid 35 under pressure in the body to increase the tension of said tension belt.

6. A wheel equipment, comprising an annular and transversely elongated body having a circumferentially inextensible tension belt arranged substantially concentric with the major transverse axis of the body in the outer portion of the body, an inner support for said belt, a transversely elongated fluid 45 tight tube within the tension belt, an annular and transversely disposed metal spring arranged substantially concentric with the major transverse axis inwardly of said tension belt, and an annular and transversely elongated cushion inwardly of the outer 50 portion of said tension belt.

7. A wheel equipment, comprising an annular and transversely elongated body having a circumferentially inextensible tension belt arranged substantially concentric with the major transverse axis of the body in the outer portion of the body, an inner support 60 for said belt, a transversely elongated fluid tight tube between the outer transversely 65 extending portion of the tension belt and

said inner support, an annular and transversely disposed metal spring arranged substantially concentric with the major transverse axis inwardly of said tension belt, and an annular and transversely arranged cushion within the tube and extending laterally throughout the major width of the construction. 70

8. A wheel equipment, comprising an annular and transversely elongated body forming a non-collapsible and universally resilient truss, said body having flexible tension elements annularly and transversely disposed, and substantially concentrically arranged relatively to the major transverse 80 axis, with curvatures at the sides forming flexing tension abutments for the annular and transverse circumferentially inextensible tension portions of said truss between such abutments, an annular and transversely elongated flexible cushioning and trussing portion in resilient abutment relationship with said flexible tension, and an annular and transversely arranged metal spring inwardly of the annular and transverse circumferentially inextensible tension portions 85 of said truss. 90

9. A wheel equipment, comprising an annular and transversely elongated body forming a non-collapsible and universally resilient truss, said body having flexible tension elements annularly and transversely disposed and substantially concentrically arranged relatively to the major transverse 95 axis, with curvatures at the sides forming flexing tension abutments for the annular and transverse circumferentially inextensible tension portions of said truss between such abutments, an annular and transversely elongated flexible cushioning and trussing portion in resilient abutment relationship with said flexible tension, an annular and transverse inner seating portion in annular and transverse inner seating relationship across the body with said flexible tension and flexible 100 cushioning abutments in and about the sides, and an annular and transversely arranged metal spring inwardly of the annular and transverse circumferentially inextensible tension portions of said truss. 105

10. A wheel equipment, comprising an annular and transversely elongated body forming a non-collapsible and universally resilient truss, said body having flexible tension elements annularly and transversely disposed, and substantially concentrically arranged relatively to the major transverse axis, with curvatures at the sides forming flexing tension abutments for the annular and transverse circumferentially inextensible tension 110 portions of said truss between such abutments, an annular and transversely elongated flexible cushioning and trussing portion in resilient abutment relationship with said flexible tension, an annular and transverse circumferentially inextensible tension 115 portions of said truss. 120

125

- verse inner seating portion in annular and transverse resilient trussing relationship across the body with said flexible tension and flexible cushioning abutments in and 5 about the sides, an annular and transversely arranged metal spring inwardly of the annular and transverse circumferentially inextensible tension portions of said truss, and an annular and transversely disposed tread 10 portion in annular and transverse resilient trussing and trussed relationship with said annular and transverse tension abutment supports. 11. A wheel equipment, comprising an annular and transversely elongated body forming a non-collapsible and universally resilient truss, said body having flexible tension elements annularly and transversely disposed, and substantially concentrically arranged 15 relatively to the major transverse axis, with curvatures at the sides forming flexing tension abutments for the annular and transverse circumferentially inextensible tension portions of said truss between 20 such abutments, an annular flexible cushioning abutment support in the sides of said flexing tension abutments, an annular and transversely arranged metal spring inwardly of the annular and transverse circumferentially inextensible tension portions of said truss, and an annular transverse 25 cushioning portion across the body between 30 said side abutments. 12. A wheel equipment, comprising an annular and transversely elongated body forming a non-collapsible and universally resilient truss, said body having flexible tension elements annularly and transversely disposed, and substantially concentrically arranged 35 relatively to the major transverse axis, with curvatures at the sides forming flexing tension abutments for the annular and transverse circumferentially inextensible tension portions of said truss between 40 such abutments, an annular flexible cushioning abutment support in the sides of said flexing tension abutments, an annular transverse cushioning portion across the body between 45 said side abutments, an annular and transversely arranged metal spring inwardly of the annular and transverse circumferentially inextensible tension portions of said truss, and fluid under pressure throughout 50 the major width of said truss. 55 13. A wheel equipment, comprising an annular and transversely elongated body forming a non-collapsible and universally resilient truss, said body having flexible tension elements annularly and transversely disposed, and substantially concentrically arranged 60 relatively to the major transverse axis, with curvatures at the sides forming flexing tension abutments for the annular and transverse truss, an annular and transversely elongated cushion in abutting relationship with the annular and transverse tension truss, and an annularly and transversely arranged metal spring combined in concentric relation with the cushion and the flexible tension elements. 70 14. A wheel equipment, comprising an annular and transversely elongated body forming a non-collapsible and universally resilient truss, said body having flexible tension elements annularly and transversely disposed and substantially concentrically arranged relatively to the major transverse axis, with curvatures at the sides forming flexing tension abutments for the annular and transverse truss, an annular and transversely elongated cushion in abutting relationship with the annular and transverse tension truss, an annularly and transversely arranged metal spring combined in concentric relation with the cushion and the flexible tension elements, and means to vary the tension of the resilient truss. 75 80 85 90 95 100 105 110 115 120 125 130

8

tially concentrically arranged relatively to the major transverse axis and merging in curvatures in and about the sides and forming radially and laterally flexing tension abutments for circumferentially inextensible portions of said truss between said abutments, an annular and transversely elongated flexible and yielding cushioning support for said tension elements, an annular and transversely disposed metal spring combined in concentric relationship with the tension and cushioning elements of said truss, and means to vary the tension of said truss.

15 18. A wheel equipment, comprising an annular and transversely elongated body forming a non-collapsible and universally resili-ent, tension, cushioning, spring truss, said body having flexible tension elements annu-

larly and transversely disposed and substan-tially concentrically arranged relatively to the major transverse axis and merging in curvatures in and about the sides and forming radially and laterally flexing tension abutments for circumferentially inextensible portions of said truss between said abutments, an annular and transversely elongated flexible and yielding cushioning support for said tension elements, an annular and transversely disposed metal spring com-bined in concentric relationship with the tension and cushioning elements of said truss, and mobile content under pressure in said truss.
